Rudolph Eberhardt ^{Inventor}
By his Attorney
Howard J. Neumann.

UNITED STATES PATENT OFFICE.

RUDOLPH EBERHARDT, OF NEW YORK, N. Y., ASSIGNOR TO REMILLER CO. INC., A CORPORATION OF NEW YORK.

DESIGN FOR A BOTTLE.

48,489.

Specification for Design.

Patented Feb. 1, 1916.

Application filed November 12, 1915. Serial No. 61,165. Term of patent 7 years.

To all whom it may concern:

Be it known that I, RUDOLPH EBERHARDT, a citizen of the United States, residing at New York city, in the county of New York and State of New York, have invented a new, original, and ornamental Design for Bottles, of which the following is a specification, reference being had to the accompanying drawing, forming part thereof.

Figure 1 is a front elevation of a bottle showing my new design. Fig. 2 is a top plan view of Fig. 1. Fig. 3 is an end elevation of Fig. 1.

I claim:

The ornamental design for a bottle, substantially as shown.

RUDOLPH EBERHARDT.
